DESIGN FOR A GAME BOARD

Peter C. Boalen, Detroit, Mich.

Application May 13, 1940, Serial No. 92,337

Term of patent 3½ years

To all whom it may concern:

Be it known that I, Peter C. Boalen, a citizen of the United States residing at Detroit, in the county of Wayne and State of Michigan, have invented a new, original, and ornamental Design for Game Boards, of which the following is a specification, reference being had to the accompanying drawing, forming part thereof, wherein:

Fig. 1 is a plan view of a game board, showing my new design.

Fig. 2 is an edge elevational view of the board.

I claim:

The ornamental design for a game board, as shown.

PETER C. BOALEN.
